(57) **CLAIM**

The ornamental design for an audio interface, as shown and described.

DESCRIPTION

FIG. 1 is a front perspective view of an ornamental design for a audio interface;

FIG. 2 is a rear perspective view thereof;

FIG. 3 is a top view thereof;

FIG. 4 is a bottom view thereof;

FIG. 5 is a first side view thereof;

FIG. 6 is a second side view thereof;

FIG. 7 is a front view thereof; and,

FIG. 8 is a rear view thereof.

The broken lines shown in FIGS. 1–8, that are immediately adjacent to the shaded areas, and define unshaded regions, represent the bounds of the claim, while all other broken lines are directed to environment and are for illustrative purposes only; the broken lines form no part of the claim.

1 Claim, 5 Drawing Sheets
